UNITED STATES PATENT OFFICE.

FRANK N. PERCIVAL AND WILLIAM PATTERSON, OF CHICAGO, ILLINOIS.

KEROSENE-CARBURETER.

1,150,619.

Specification of Letters Patent. Patented Aug. 17, 1915.

Application filed July 9, 1913. Serial No. 778,009.

To all whom it may concern:

Be known that we, FRANK N. PERCIVAL and WILLIAM PATTERSON, citizens of the United States, residing at Chicago, in the county of Cook and State of Illinois, have invented a certain new and useful Improvement in Kerosene-Carbureters, of which the following is a specification.

This invention relates to carbureters used upon gas engines, particularly for use upon automobiles and tractor engines, in which kerosene, paraffin, or other substances less volatile than gasoline are to be used as a fuel.

The object of the invention is to provide such a carbureter which will readily convert such fuels into condition where they may be readily taken up by the air passing through the carbureter.

The invention consists in a device capable of carrying out the foregoing objects which can be easily and cheaply made, installed and operated and particularly one which may be used in starting a cold engine.

More in detail the invention consists in a carbureter equipped with heating means, more particularly an electric heating means, for rendering the fuel materials readily usable.

It also consists in means for regulating and controlling the supply of fuel material to the heating means and in other details to be hereafter described.

In the drawings, Figure 1 is a sectional detail view through a device illustrating this invention in its preferred form. Fig. 2 is a sectional detail view on the line 2—2 of Fig. 1.

The carbureter has an exterior casing 10 having suitable means for support on an engine, such for instance as the flanges 12 about the top opening 14 normally communicating with the suction or intake pipe (not shown) of an engine. This opening is closable by any convenient sort of a valve 16, pivoted for instance at 17 and operated by a lever 18. The lower portion of the carbureter body 10 has a contracted neck in which the end 22 of the fuel nozzle 24 is inserted as shown in the drawings so that there is a restricted passageway 20 between them. The nozzle 24 enters the lower portion of the casing 10 through a suitable opening, provided for the purpose, closed by a bushing and packing ring device 26 of any suitable form. The upper end of the fuel

nozzle 24 is provided with at least one perforation 28 through which fuel material is delivered into the carbureter.

Extending through the central upper portion of the carbureter body 10 is a tubular passageway 30, having at one side an entrance port 31, and at the other side a discharge port 32. Closely fitted into this passageway 30 is a radiator device comprising two perforated heads 34 connected by a plurality of tubes 36 clearly shown in Fig. 2 for the passage of air. The discharge port 32 is connected by a suitable pipe 38 to an air port or passageway 40 located on the side 70 of the carbureter body 10 and below the restricted passageway 20 heretofore referred to.

The result of the foregoing construction is that when air is drawn by any suitable means, into the entrance port 31, it passes from that port through the tubes 36, the pipe 38 and the passageway 30 into the space 42 in the interior of the carbureter below the restricted opening 20 from which position 80 it passes through that opening upward through the chamber 44 into the upper portion of the interior of the carbureter around the outside of the pipes 36 and thence out of the discharge port 14 into the engine. It 85 will also be seen that if fuel material of a higher temperature than the incoming air be inserted in and delivered from the fuel nozzle 24, the passing air will acquire heat both from contact with the exterior wall of 90 the fuel nozzle 24 and by contact with the liquid fuel sucked through the discharge port 28 and be thus raised to a higher temperature than the air entering the port 31, with the result that this mixture contacting 95 the exterior portions of the pipes 36, warms them and consequently the incoming air which passes through the interiors of said pipes 36, that is to say, the incoming air passing through the insides of the pipes 36 100 is warmed somewhat before it reaches the opening 20 and thus does not require so much heat at that point to raise it to proper temperature for efficient working.

In order to supply hot fuel material inside of the fuel nozzle 24 without waste of energy, an electric heating device is provided inside the fuel nozzle. This device may take various forms but the preferred form here shown consists in an exterior tube 105 50 entering the fuel nozzle 24 through stuffing box devices 52, there being placed with-

in the tube 50 rods 54 and 56 connected between their ends by suitable resistance wire 58 so that when electric current is passed from any suitable source, as for instance an ordinary battery or storage battery, through the wires 59 connected to the terminals 60 of the rods 54 and 56, the resistance device inside the tube 50 becomes hot and thus delivers heat to the fuel material which is inside of and passing through the fuel nozzle 24 about the tube 50.

The fuel for the nozzle 24 is introduced through suitable piping 62 leading to a regulating tank 64 which is in turn supplied with the fuel by a pipe 66 having, if desired, a suitable drainage cock 68.

Slidably mounted in the end portion of the pipe 66 and through the tank 64 is a valve rod 70 having on its lower end a ball 71 normally seating in the angular valve seat 74. Rigidly secured to the rod 70 is a float 75 adjustable up and down the rod by screw threaded nuts 78 thereon. The tank 64 is closed by a cover 72 from which rises a support 73 on which is pivoted a lever member 76 one end engaging the upper end of the rod 70 and the other end being connected to a pull wire or rod 78. The lever 76 is normally held in the position shown in the drawings by a suitable spring 80.

Inserted through the cover 72 is preferably an electrical heating device 82 of any suitable construction such for instance as that which is contained within the fuel nozzle 24. This heating device is supplied with electric current by a source of electric energy connecting to wires 84. The float 75 is so shaped as shown that it clears the electric heater 82 and therefore, the float can move up and down without interference with the heater.

In the operation of the device, liquid fuel from any suitable device is constantly supplied to pipe 66 and when the operator pulls upward on the rod 78 to rotate the lever 76 in a clockwise direction thereby depressing the rod 70 and ball 71 so that said ball clears the valve seat 74 said liquid passes around the ball 71 and the rod 70 into the interior of tank 64 in which said liquid rises to the height indicated by the line $\alpha-\alpha$. Fig. 1. Float 75 is so adjusted that when the liquid in the chamber 64 does thus rise to the height of the line $\alpha-\alpha$, the float will obviously move upward to the position shown in the drawings in which the valve 71 is seated upon its seat 74 and the supply of liquid is cut off from the pipe 66. It is obvious that any liquid in the chamber 64 will flow through the pipe 62 into the fuel nozzle 24 and surround the cylinder 50 with the heating device therein and that it will rise in said fuel nozzle to the exact height of the liquid in the chamber 64 and the de-

vice is therefore, so adjusted that the liquid will thus rise in the fuel nozzle 24 to the height of the line $\alpha-\alpha$ or the top of the nozzle before the float 75 causes the valve 71 to close. In other words, the float 75 is so adjusted that the liquid can never overflow the top of the fuel nozzle 24 and flow out of the opening or openings 28 therein while on the other hand if a sufficient pressure of fuel liquid is provided in the pipe 66 the liquid will always be maintained in the fuel nozzle at the height of the line $\alpha-\alpha$. When now the liquid has been turned into the pipe 66 and has thus passed through the chamber 64 to the top of the fuel nozzle 24 and electric current has been supplied to the heating device within the fuel nozzle, it is obvious that the fuel in the fuel nozzle will be heated to a more or less high temperature. In starting the apparatus the operator manipulates the device until this result is attained whereupon he starts the engine, not shown, attached to port 14 and thus draws air into the entrance port 31 and thence through the radiator 36, pipe 38, passageway 40, the chamber 42 and the restricted opening 20 adjacent to the exit port 28 of the fuel nozzle 24. The passing of the air through this restricted passageway 20 creates a slight vacuum with resulting suction which draws liquid from the fuel nozzle through the opening or openings 28 with resulting mixing of the air and liquid fuel. This mixture of air and fuel previously heated in the manner described passes upward around the outsides of the radiator pipes 36 and thence through the exit passageway 14 into the engine. In actual practice it is found that by turning the fuel, i. e., kerosene into the device and starting the heater in the fuel nozzle and allowing the apparatus to stand in this condition for one minute before the engine is cranked to draw in the air, the kerosene can be used satisfactorily in the starting of a cold engine.

A supplementary valve device 83 normally held on its seat 85 by a spring 86 may be provided, if desired, to admit air to the mixing chamber.

The heating device 82 operates to partially heat the fuel in the chamber 64 before passing into the fuel nozzle 24 thereby reducing the work required of the heating device within said fuel nozzle.

If desired a supplemental electric heater 100 supplied by wires 102 may be installed in connection with the pipes 36 to heat both the incoming air and the mixture moving away from nozzle 22. This is of assistance in starting.

It will be noticed that the use of the tube 50 inside the nozzle 24 as the container for the heater affords a maximum size heating surface inside the nozzle for contact by the

passing oil, thus enabling the device to give more satisfactory results than where the liquid is passed through a small passageway in the center of the heater.

5 Having thus described our invention, what we claim as new and desire to secure by Letters Patent, is:

- 10 1. A carbureter including a carbureting chamber through which air is adapted to pass, and a fuel nozzle entering the chamber so as to discharge combustible material into the passing air, means for heating the combustible material as it is discharged in the carbureter, and means conducting air to the carbureter nozzle located in the path of the discharge from said nozzle so that the incoming air is warmed by the material discharged from the nozzle, for the purposes set forth.
- 20 2. In a device of the class described, a carbureter having a casing provided with a discharge port adapted to be connected to the intake of an engine, an air entrance port for admitting air to a carbureting chamber within the casing through a restricted opening 20, an air pipe or passageway between

said restricted opening 20 and said discharge port including radiator pipes passing through the carbureter body and thence connected to said entrance port of the carbureter, a fuel nozzle entering the carbureter body and having a discharge port in proximity to said restricted passageway 20, means for regulating and supplying combustible material to said discharge opening 35 of the nozzle, and means located within the carbureter for heating such combustible material within the fuel nozzle adjacent to said discharge opening, and a heating device 100 adjacent to said radiator pipes, all of the 40 parts being arranged and disposed substantially as shown and described for the purposes set forth.

In witness whereof we have hereunto subscribed our names in the presence of two 45 witnesses.

FRANK N. PERCIVAL.
